DESIGN FOR A WASHING MACHINE

Thomas R. Smith, Newton, Iowa

Application July 20, 1939, Serial No. 86,113

Term of patent 14 years

To all whom it may concern:

Be it known that I, Thomas R. Smith, a citizen of the United States, residing at Newton, in the county of Jasper and State of Iowa, have invented a new, original, and ornamental Design for a Washing Machine, of which the following is a specification, reference being had to the accompanying drawing, forming a part thereof.

In the drawing:

Fig. 1 is a perspective view of a washing machine showing my new design.

Figure 2 is a view similar to Fig. 1 but showing the washing machine rotated through approximately 180°.

I claim:

The ornamental design for a washing machine, substantially as shown.

THOMAS R. SMITH.
